UNITED STATES PATENT OFFICE

ERNEST THOMAS FISK, OF SYDNEY, NEW SOUTH WALES, AUSTRALIA

SOUND SUPPRESSING VENTILATOR FITTING FOR WINDOWS

Application filed June 27, 1928, Serial No. 288,763, and in Australia July 27, 1927.

The object of this invention is to provide improved means whereby when windows are opened in noisy localities to permit effective ventilation the incoming sound waves will be absorbed or damped in a satisfactory degree.

5 The devices herein proposed for this purpose tend to promote ventilation rather than to retard it through the opened window space. They also operate to reduce the heating of apartments by reflected rays from without and to check entrance of rising currents of hot air and also to check the incoming of dust from the street.

10 The invention is illustrated in the accompanying drawings in which Fig. 1 is a vertical transverse section through a sliding sash window, and Figs. 2, 3 and 4 are views similar to Fig. 1 illustrating modifications of the invention.

15 The device in which the invention consists is constituted of two panels disposed in angular relation one above the other, one panel 10 being a sound dampening structure containing ventilating apertures, and the other panel 11 being transparent or translucent to permit the passage of daylight. The lower panel 10 extends outward, or outward and upward from the lower edge of the window aperture; the upper panel 11 extends upward, or upward and inward from the outer edge of the lower panel 10. If the apparatus is erected within the reveal the sides of the latter form closures, thus completing a hopper-shaped structure capable of being opened at the top, 20 and its bottom opened only through the sound absorbent ventilating apertures. When the apparatus cannot be fitted within the reveal it is necessary to protect the sides against the entry of sound waves and this can be done by fitting panels such as 13 of transparent, 25 translucent or opaque material.

30 Either the upper or lower panel or both may be mounted on hinges so that their angular adjustment can be altered at will; or both panels may be fixed.

35 The panel 10 may be constructed of a sheet of sound absorbent material 18, containing ventilating apertures 14 as in Fig. 2. Alternatively, the panel may be constructed as a 40 box-like structure as in Figs. 1, 3 and 4, the

sides of the box being closed and the top 15 and bottom 16 of the box apertured as at 17. This cellular panel may be constructed of sound absorbent material such as is known under the trade mark "Celotex", or it may be 45 constructed of other material and lined with sound absorbent material as shown at 20 in Fig. 3. The upper face of the sound absorbent panels 10 and 18 may be surfaced with light reflecting material to facilitate transmission of daylight into the apartment.

50 Referring to Fig. 1, the cellular panel 10 is hingedly mounted at 21 on the sill; 22 is a stay for holding it in the desired position. The upper panel 11 is hinged at 23 to the panel 10 and is held in adjusted position by the stay 24; it is shown in vertical position in full lines and in its tilted position touching the sash, in dotted lines. When the panel 11 is disposed in a substantially vertical direction a flue effect is obtained, so that in most cases a more satisfactory exchange of air is procured than in the case of an ordinary open window. Warm air currents rising from below promote an upward draught which tends to draw air out of the apartment, giving the effect of an exhaust ventilator. Cool air currents moving downward from above are deflected inward, thus tending to replenish the 55 apartment with fresh air. The outside air currents thus operate sometimes to promote inflow and at other times to promote outflow of air.

60 By inclining the free edge of the panel 11 away from the window aperture the amount 55 of ventilation can be regulated in any measure that may be desired; if it be tilted toward the aperture sufficiently to contact with the sash face or the sill, ventilation is then obtained only through the perforations through 65 the cellular panel. This control is advantageous in cold weather when a small degree of distributed ventilation is all that is needed. Such tilting of this panel also may be employed to check the entry of rain or snow into 70 the apartment.

75 Fig. 2 shows a sash window fitted with a sound absorbent perforated panel 18, hingedly mounted by a double-fold hinge 25 to the sill to permit it and the upper panel 11a to 80

be swung inward and suspended when not in use, as indicated in dotted lines. The upper panel 11a is hinge mounted on the lower panel as in the Fig. 1 construction and stays 22a and 24a are provided for holding the panels in position. The spaces at the sides of the fitting are in this case closed by means of wing panels 13 which are hinge mounted on the sides of the top panel 11a so that they 10 may be folded against it when not in use, as for instance, when the fitting is swung into the apartment as shown in dotted lines.

Fig. 3 is a view similar to Fig. 2 but showing wing panels on the panel 10a as well as 15 on the panel 11b, and a cellular sound absorbent panel 10a. This view also shows in dotted lines how the fitting is dropped and held suspended below the window opening when not in use.

20 Fig. 4 shows a fitting erected as a permanent fixture extending horizontally from the sill, with rectangular wing panels 13c closing the spaces between the upper panel 11c and the wall face. In this view the cellular panel 25 is shown lined with sound absorbent material 20.

The fitting illustrated in Fig. 4 may be erected on casement windows, and the sashes of the casement may be used to take the place 30 of the wing panels 13c.

What I claim as my invention and desire to secure by Letters Patent is:—

1. In combination, a wall having an aperture and a sill, a sound suppressing ventilator 35 fitting, including a perforate panel at the level of the sill and disposed substantially in a horizontal position, and a second panel arranged above the first panel disposed in substantially a vertical position, and means for 40 securing the second mentioned panel in various adjusted positions to vary the degree of ventilation.

2. In combination, a wall having an aperture and a sill, a sound suppressing ventilator 45 fitting, including a perforate panel at the level of the sill and disposed substantially in a horizontal position, and a second panel arranged above the first panel disposed in substantially a vertical position, means mounting 50 the first panel for swinging movement about one of its edges and means mounting the second panel for movement about another edge of the first panel.

3. In combination, a wall having an aperture, a lower panel of sound absorbent material having ventilating apertures and extending outward from the wall aperture, and an upper panel of light transmitting material extending upward from the outer edge of the 60 lower panel, said lower panel having an upper light reflecting surface.

4. In combination, a wall having an aperture and a sill, two main panels fitted outside the wall aperture one above the other, the 65 lower panel being of sound-absorbent struc-

ture and having ventilating apertures and extending outward from the sill and the upper panel being adapted to transmit light and extending upward from the outer edge of the lower panel, and lateral panels in the spaces between the wall and the panels.

In testimony whereof I affix my signature.

ERNEST THOMAS FISK.
